NEW YORK

GUTTER HANGER

Application filed October 13, 1928. Serial No. 312,277.

This invention relates to gutter hangers, having particular reference to improved means for securing the outer or rolled edge of the gutter to the circle.

5 The primary object of the invention is to provide means of simplified and improved nature whereby the free end of the circle and the rolled edge of the gutter may be securely and rigidly interlocked, which interlocking 10 maintains the parts practically as a unitary structure but which is of such nature as will permit of the ready disengagement of these parts when required.

A further object of the invention is to provide means of the character stated embodying such structure that the operations of bringing about the interlocked condition are extremely simple and do not require the exercise of special skill or tools.

20 A still further and particular object is to so construct the outer end of the circle and the parts associated therewith as not to detract from the efficiency either of the circle or the gutter, which enables the inventive 25 idea to be carried out at a minimum of cost and yet which will prove highly practical and effective in use.

With these objects in view, together with others which will appear as the description 30 proceeds, the invention consists in the novel construction, combination and arrangement of parts, all as will be described more fully hereinafter, illustrated in the drawings and particularly pointed out in the claims.

35 In the drawings:—

Fig. 1 is a side elevation of a circle constructed in accordance with the invention and illustrating a gutter applied thereto.

Fig. 2 is a fragmentary front elevation of 40 the outer end of the circle.

Fig. 3 is a fragmentary view similar to Fig. 1 and illustrating a slight modification of the invention.

Fig. 4 is a detail view of a preferred form 45 of securing strap or cleat, and

Fig. 5 is a detailed perspective view of a circle and embodying a slight modification of the invention.

In the drawing, 6 indicates generally the 50 gutter supporting circle, formed preferably

of sheet metal and of U-shape in cross section whereby webs 7 depend from the longitudinal edges of the supporting portion of the circle in spaced parallel relation. The inner end of the circle may be attached to a shank 55 in any preferred manner, and may be equipped with any desired means for attaching the inner edge of the gutter thereto.

The outer extremity of the circle is formed with a prong 8 projecting forwardly therefrom to engage and wedge beneath the roll portion 9 of the gutter, in a manner generally understood. The outer extremities of the webs 7 are cut and bent inwardly toward each other to provide a wall 10 constituting the upper or outer extremity of a pocket 11. This pocket is formed between the webs 7 and the wall 10, and it is preferred that the metal constituting the wall 10 be cut so that when the said portions are bent inwardly into engagement with each other, the wall will be disposed at a downwardly and outwardly inclining angle to the free end of the circle. This wall, furthermore, is positioned a substantial distance below the free end of the 75 prong 8. The means for tying the rolled portion of the gutter to the end of the circle includes a strap or cleat 12 formed of strong but pliable metal, one end of which is disposed at an angle to provide a tongue 13 to 80 engage beneath the wall 10. The cleat or strap is of such length as to reach up from the pocket and around the roll 9 of the gutter as shown. To lend rigidity to the cleat or strap, it is proposed to incline the longitudinal edges thereof 14 at a substantial angle to the body portion of the cleat.

It has been proposed heretofore to provide a tongue near the end of the circle and to have a flexible strap with an opening therein 85 to engage with said tongue and then be formed around the roll in a manner similar to that above described. A serious objection to this practice, however, is that once the tongue becomes broken, which very frequently occurs, the circle is useless and must be abandoned. By providing the pocket in the manner stated above and having the cleat equipped with the tongue, no damage whatever can occur to the circle in the applying operation but if the 100

retaining tongue 13 becomes broken, it is only necessary to provide a new cleat, which may be readily done at very small cost. By disposing the wall 10 at the angle described, it will be impossible for water to accumulate beneath the same to cause corrosion, and furthermore, such inclination of the wall permits of the tongue 13 being disposed at such angle to its body portion as to minimize the opportunity for breaking away or bending straight. The distance from the base of the tongue to the inner end of the wall 10 is greater than the distance from the outer edge of the web 7 to the base of the circle, so that when the tongue is engaged within the pocket and lying flush against the wall 10 thereof, bending of the free end of the cleat around the roll of the gutter will create a locking action that will preclude accidental disengagement of the tongue from this pocket.

In Fig. 3 of the drawing there is shown a slight modification of the invention, wherein in the circle is provided in its base immediately beneath the wall 10 with an aperture or opening 15 to receive a hook or projection 16 at the free end of the tongue 13. By providing such a hook, additional securing means are thus provided for the retaining end of the cleat, and accidental disengagement is positively prevented. It has been customary to provide the base of the circle 6 with a longitudinally disposed depression 17 to permit of the circulation of air between the circle and the gutter and to permit of drainage, and the aperture 15 may be located in the bottom of such depression and thus permit of the hook 16 engaging with the base of the circle without coming into injurious contact with the gutter.

In Fig. 5 there is illustrated a modification of the invention which shows the adaptability of the inventive idea to circles of that type wherein but a single flange or web is provided. The web is represented at 7 and may depend from either edge or the middle portion of the circle. The outer end of the web may be cut and bent inwardly to provide the wall 10 and downwardly to provide a side lock 18 to prevent the tongue 13 becoming disengaged from beneath the wall. In this form of the invention the opening 15 may be used if desired, or eliminated.

From the foregoing it is apparent that we have provided extremely simple yet fully effective means for bringing about a locking action between the outer end of the circle and the gutter roll. The circles, of whatever approved design employed, may be easily cut and bent at their outer ends to provide the retaining wall and pocket for the cleat hook. The hooks may be made at an extremely nominal cost, as they comprise nothing more than a ribbon of pliable metal of proper length and provided at one end with a tongue, which tongue may be of a width

equal to or less than the breadth of the strap as desired.

Having thus described our invention, we claim:

1. In a gutter hanger, a circle to receive the gutter, a pocket at one end of said circle, a cleat formed of flexible metal, and a tongue at one end of said cleat to engage and lock in said pocket. 70

2. In a gutter hanger, a circle, a web depending from said circle, a wall formed by said web and bent laterally across said circle, and a cleat formed of flexible metal and having a tongue at one end to engage beneath said wall. 75

3. In a gutter hanger, a circle, a web depending from said circle, a portion of said web bent across the lower side of said circle to form a wall disposed at an angle thereto, a cleat comprising a strap of pliable material, a tongue at one end of said cleat, said tongue bent to lie flat against the under face of said wall, and the length of said tongue being greater than the radial depth of said web. 85

4. In a gutter hanger, a circle to receive the gutter, a pair of spaced webs depending from said circle, the ends of said webs cut and folded inwardly into engagement with each other to provide a pocket, a cleat, and a tongue at one end of said cleat to engage within said pocket. 95

5. In a gutter hanger, a circle to receive the gutter, a prong at the end of said circle to engage with the roll of the gutter, webs depending from said circle, said webs folded inwardly toward each other to provide a wall, a cleat, a tongue at one end of said cleat to engage beneath said wall, and said cleat adapted to be bent around the roll of said gutter. 105

6. In a gutter hanger, a circle to receive the gutter, said circle having a depression in the bottom thereof, webs depending from said circle, said webs bent toward each other to provide a wall, said depressed portion having an aperture therein lying directly beneath said wall, a cleat, a tongue at one end of said cleat to engage with said wall, and a hook at the extremity of said tongue to engage through said aperture and lie confined within said depression. 110

In testimony whereof we hereby affix our signatures.
